TIME-LIMIT CIRCUIT-BREAKER.

1,144,233.

Specification of Letters Patent. Patented June 22, 1915.

Application filed November 23, 1911. Serial No. 661,979.

To all whom it may concern:

Be it known that I, MICHAEL F. OWENS, a citizen of the United States, a resident of Hartford, in the county of Hartford and State of Connecticut, have invented certain new and useful Improvements in Time-Limit Circuit-Breakers, of which the following is a full and clear specification, illustrated in the accompanying drawings, the particular novel features of the invention being more fully pointed out in the annexed claims.

My invention relates in general to circuit breakers which control the current supplied to electric motors, whereby the current is interrupted when it exceeds a predetermined amount, and in which besides by suitable means such excess of current is permitted to flow to the motor during a predetermined time.

In particular my invention relates to circuit breakers which permit an excess amount of current to flow to the motor during its starting period, whereafter the sensitiveness of the device is varied so that the current will be interrupted whenever it should exceed a predetermined limit.

The accompanying drawings illustrate a wiring arrangement and the necessary apparatus in diagrammatic form, since the detail construction of the apparatus in particular may vary considerably according to the requirements in every given instance.

In these drawings Figure 1 represents a diagrammatic arrangement of circuits in which a two phase alternating current motor is controlled, whereby the main current is interrupted indirectly through the opening or closing of auxiliary circuits. Fig. 2 represents a diagrammatical illustration of similar character to that shown in Fig. 1 applied to a motor supplied by three phase alternating current, and Fig. 3 is a diagrammatical illustration of a two phase alternating current supply, whereby the main current is directly interrupted by the cut-out device.

In all three figures the wires which carry the main current supplied to the motor are indicated by heavy lines, whereas what are termed hereinafter the auxiliary circuits are indicated by light lines.

Referring to the modification shown in Fig. 1, *a*, *b*, *c* and *d* are four mains or con-

ductors through which the two phase alternating current is supplied. 1 is the main switch which may be opened or closed by hand. *M* is the motor to which the current is supplied. The diagrams which I have illustrated in all three figures are in their arrangement particularly adapted to the control of an electric motor for driving refrigerating machinery, and therefore I have shown the automatic control of the starting and stopping of the motor as effected by a thermostat, which in all three figures is shown at 2. Moreover refrigerating systems of the kind for which the system is intended are also nowadays generally provided with what might be termed a high pressure cut out which responds to dangerously high pressure in the refrigerating system, and whereby the motor is stopped instantly as soon as this pressure has been attained. Systems of this kind are for instance described in a patent to Chamberlain and Marshall, No. 834,870, issued October 30th, 1906, and merely for the sake of completeness I have inserted diagrammatically a switch which interrupts the motor current at such excessive pressure also in the present system, in order to indicate where such high pressure cut out device may be located in my novel cut out device. In all three figures the high pressure cut off switch is indicated at 3, and in all three instances it is assumed that this switch remains closed.

In Fig. 1 the cut out controller is shown at 4 and it consists of two solenoids 5 and 6 each provided with a core 7 and 8 respectively, which cores in deenergized condition of the solenoids protrude at the lower ends of their coils and are arrested in this position by a stop 9 which may be integral with the base plate, not shown, on which the whole device is mounted. The lower end of each core is provided with a lug 10, each of which cooperates with a bell crank 11. Each of these bell cranks has one arm provided with a latch 12 adapted to engage lug 10 of its adjacent core, while the other arm 13 of each of the two bell cranks extends horizontally as clearly shown. Moreover each bell crank, which is pivoted at 14, has a detent 15 to which a spring 16 is attached in such manner that each bell crank tends to engage with its latch 12 the lug 10 of its adjacent core. Between arms 13

extends a substantially vertical rod 17 which has attached to it a weight 18 in line with arms 13 so that when it descends it strikes these arms and thereby removes latches 12 from their respective lugs, and to thus render cores 7 and 8 free to move upward. Rod 17 also carries near its lower end core 19 of a solenoid 20 which is in such position that when the solenoid is energized its core 19 is drawn upward and thus removes weight 18 from bell crank arms 13. The lower end of rod 17 carries a piston 22 of a dash pot 21 which operates in such manner that the piston is free to move upward but its downward movement is retarded by the action of the dash pot which may be controlled through valve 23. Thus when solenoid 20 is energized and draws in its core 19, rod 17 with weight 18 is free to fly upward, but when the solenoid is deenergized core 19 with its weight 18 will gradually sink back under the influence of the dash pot into its normal position shown. The upper end of rod 17 carries a switch 24 which is closed when the rod 17 moves upward, and which is opened when this rod starts on its downward movement. Moreover each core 7 and 8 of solenoids 5 and 6 respectively carries on its upper end a rod 25, each of which by its upward movement opens a contact 26 by impinging upon a lever 27 pivoted at 28. The main switch 30 which opens and closes the circuit, directly leading to the motor may have any form known in the art which is suitable for control by a solenoid or the like. I have for instance shown in this particular instance a toggle joint switch which has two arms 31, 32, pivoted at 33 and 34 respectively. The arms coöperate with the contact elements 35 and 36 respectively. The switch is operated by a rod 37 the lower end of which carries a solenoid core 38 which protrudes through the lower end of a solenoid 39 and its upper end is connected with an auxiliary switch 40 which may be of any suitable construction. In this particular instance I have illustrated simply a lever 42 pivoted at 41 and pivotally connected with rod 37 which carries at its other end an insulated body 43 carrying two contact plates 44 and 45 respectively, by which the auxiliary conductors shown adjacent to these plates are connected with each other in the manner which will be presently described. The thermostat 2 previously referred to has a "start" and a "stop" contact. The connection between the several devices previously described is as follows, (main switch 1 being assumed as closed:) From conductor *d* the current runs over switch 1, to auxiliary conductor 50, to thermostat 2, which is assumed to stand on the start contact, thence over conductor 51, to plate 44, and over conductor 52 to solenoid coil 20, and thence over conductor 55 to main conductor *c*, without passing again through switch 1. This energizes solenoid 20 and the latter by attracting its core 19 throws up weight 18 without thereby encountering the resistance of the dash pot 21. By this movement of rod 17 switch 24, disposed at its upper end, closes its contacts and simultaneously, by the removal of weight 18 from arms 13 on which it normally rests as described, latches 12 are permitted to lock solenoid cores 7 and 8 in the position in which they are shown. By such locking the result is obtained that should solenoids 5 and 6 be energized by an excess amount of current which is conducted to the motor in the manner to be described, cores 7 and 8 can not be drawn into their coils. The closing of contact 24 closes the following circuit: from conductor *d* over conductor 50, switch 3 (assumed to be closed), thence conductor 56 to contact 26 (normally closed), thence over conductor 57 to the other contact 26 (also normally closed), thence over conductor 58 to solenoid 39, conductor 59, resistance 60, conductor 61, switch 24, conductor 62, back to main conductor *c*. This circuit energizes solenoid 39 which thereby operates the toggle joint of the automatic motor switch 30, so that the latter is closed thereby. By the upward movement of rod 37, when switch 30 is closed, auxiliary switch 40 is thrown upward which causes its contact plate 44 to slide off conductors 51 and 52 and its contact plate 45 to connect conductors 63 and 64. This break between conductors 51 and 52 opens the circuit through the thermostat 2 and solenoid 20, so that the latter drops its core 19, which, however, can only descend slowly on account of the retarding action of dash pot 21. On the other hand the connection between conductor 63 and 64 through plate 45 establishes a passage from solenoid 39 and resistance 60, over resistance 65, conductors 63, 64 and 66, back to main conductor *c* in parallel with the connection over conductor 61, switch 24 and conductor 62 to the main conductor *c*. This shunt passage over resistance 65 is maintained as a shunt only for an instant, because at the moment solenoid 20 is deenergized and its core commences to descend switch 24 is opened, so that thereby the circuit over conductor 61, switch 24 and conductor 62 to the main *c* is interrupted. Thus notwithstanding the opening of contact 24, the circuit through solenoid 39, which controls motor switch 30, is not interrupted but the amount of current is only slightly lessened owing to resistance 65 being now interposed in this circuit. This will prevent undue heating of solenoid 39 by the current which now need only be strong enough to hold core 38 attracted. The closing of motor

switch 30 now connects mains *a*, *b*, *c* and *d* with the motor through the following four lines: main *a*, switch 1, conductor 67; main *b*, switch 1, conductor 68, solenoid 6, conductor 69, switch contact 36, over switch 30 and conductor 70 to the motor; from main *c* over switch 1, conductor 71 to the motor; from main *d* over switch 1, conductor 72, to solenoid 5, conductor 73, contact 35, 10 switch 30, over conductor 74 to the motor. Thus it will be noted that the main current of the phases *a*, *b*, and *c*, *d* respectively passes through solenoids 6 and 5. These solenoids are dimensioned so that they are 15 not able to attract their respective cores at the normal running current of the motor, but they will operate their cores at the strong current which passes through the motor during the starting period. From 20 the previous description it appears that immediately after main switch 30 is closed solenoid 20 is deenergized so that weight 18 starts to descend, and also that during the raised position of weight 18 cores 7 and 8 25 are locked. Thus when the motor starts upon closing of main switch 30, solenoids 5 and 6, while sufficiently energized by the excessive starting current, are unable to attract their core, because they are locked by 30 latches 12. The dash pot 21 is set so that it will permit its piston and thus weight 18 to descend within a predetermined time considered sufficient to accelerate the motor to full speed so that its current will fall to 35 normal. Therefore when after the lapse of this time weight 18 arrives at the bottom of its stroke and impinges upon arms 13, whereby latches 12 are withdrawn from their respective armatures 7 and 8, these 40 cores are unlocked and are now free to be drawn into their respective solenoids 5 and 6, which latter, however, on account of the starting current in both phases having now fallen to normal, are unable now to attract 45 their cores. If on the other hand after such predetermined time through some cause the motor should not have attained its full speed or the current should still be of abnormal strength, which should call for an opening 50 of the motor circuit, such abnormally strong current energizes solenoids 5 and 6 sufficiently to attract their cores. By the upward motion of cores 7 and 8 their rod 25 impinges upon its lever 27 and the two contacts 26 are opened thereby, so that the auxiliary circuit through solenoid 39 which controls the motor switch 30 is opened. Through the deenergizing of this solenoid 39 resulting therefrom, the motor switch 60 30 is opened and thus the main current cut off. This also returns auxiliary switch 40 to its normal position shown. The interruption of the main current also deenergizes solenoids 5 and 6 so that their cores 7 and 65 8 drop. Switches 26 are of such construc-

tion that they remain open even if cores 7 and 8 drop back to their usual positions, to prevent automatic starting of the motor. This may be obtained for instance by properly weighting the upper contact arms of 70 these switches, so that they tumble inwardly when their lower arms are lifted by the cores 7 and 8, respectively. In order to enable the device to start the motor, these switches must first be closed by hand, which thus calls the operator's attention to the abnormal condition of the entire system. After these switches are closed by hand all elements are returned into their normal position and ready to start the motor up again 75 if the thermostat remains on the starting contact. If during the normal running of the motor the condition of the refrigerating system should call for the stopping of the motor, thermostat 2 in this case moves to the 80 stop contact. This closes a shunt circuit by the way of thermostat 2, conductors 76 and 59, resistances 60 and 65, over conductors 63, 64, 66 to main *c*. Solenoid 39 is practically deenergized thereby or at least its 85 current is reduced to such an amount that it is unable to hold its core 38 and thus motor switch 30 is opened and the current cut off the motor. Similarly to the manner 90 previously described all the other elements 95 of the system return into their normal position shown.

It will be obvious to any one skilled in the art that the entire arrangement as previously described may be also applied to any 100 other alternating current system, for instance three phase alternating current. In Fig. 2 I have shown how the starting of a three phase alternating current may be controlled. In this figure all the elements corresponding to those shown in Fig. 1 are provided with the same reference numerals. By comparing Figs. 1 and 2 it will be noted 105 that the two arrangements differ only in the omission of main conductor *a* of Fig. 1 in Fig. 2. This main conductor *a* in Fig. 1 it will be noted runs directly over hand switch 1 to the motor. To avoid repetition I have therefore omitted to further 110 describe the arrangement in Fig. 2. 115

In Figs. 1 and 2 I have shown an arrangement in which, when an excess amount of current continues flowing through solenoids 5 and 6 beyond the predetermined time set by the dash pot, the cores of these solenoids 120 are released by weight 18 and are attracted and interrupt the auxiliary current at switches 26, so that the auxiliary current through the solenoid 39 of automatic motor switch 30 is interrupted and thus the 125 latter switch is opened. In Fig. 3 I have illustrated how instead of interrupting the circuit through solenoid 39 the main motor circuit may be interrupted by switches 26 of cut out controller 4 in case of con- 130

tinued excess of amount of current. The general arrangement which embodies this feature may be otherwise the same as the one shown in Fig. 1, and similarly to Fig. 1 I have shown this modification applied to a two phase alternating current system. Likewise all conductors and elements which this modification has in common with Fig. 1 are denoted with the same reference characters. Fig. 3 differs from Fig. 1 in the omission of the auxiliary connection 56, 57 and 58 leading from switch 3 to solenoid 39, in which connections the two switches 26 of the cut out control 4 are located in Fig. 1. Instead solenoid 39 is directly connected in Fig. 3 by conductor 80 with switch 3 and thence over conductor 50 with the main *d*. The other end of solenoid 39 is connected with the system exactly in the same manner shown and described with reference to Fig. 1, so that a description thereof as well as of the connection of solenoid 20 may be omitted from the description. Now instead of connecting switches 26 of cut out controller 4 in series with the auxiliary circuit of solenoid 39 as just described, I connect these switches in circuit with the main conductors leading to automatic switch 30. In Fig. 1, for instance, one main circuit leads from main conductor *d* over switch 1, conductor 72, solenoid 5, conductor 73 to contact 35 of the automatic switch. Another circuit leads from main *b* over switch 1, conductor 68, solenoid 6, conductor 69 to the other contact 36 of the automatic switch. I now place switches 26, which are opened when cores 7 and 8 of solenoids 5 and 6 are attracted, into these two main circuits in such manner that the circuit from main *d* leads over switch 1, conductor 72 to switch 26, thence from the other contact element of this switch over solenoid 5 and conductor 73 to contact 35 of the automatic switch 30, from where it runs the motor by way of conductor 74. The other circuit runs from main *b* over conductor 68 to the other switch 26 and thence from this other contact element over solenoid 6 and conductor 69 to contact element 36 of switch 30, whence it passes over the switch and conductor 70 to the motor M. If now, as described in detail with reference to Fig. 1, in the present arrangement an excess amount of current should continue flowing into the motor after the predetermined time has elapsed, cores 7 and 8 of solenoids 5 and 6 are released by weight 18 and drawn into their coils, whereby, as also previously described, they open switches 26. Thus in this case the two main circuits leading to the motor from the main conductors *b* and *d* respectively are interrupted which, however, in this case, occurs without opening automatic switch 30. This calls the operator's attention to the irregularity in the

starting or running of the motor, which after being cut off as described cannot start again unless the operator closes switches 26 by hand, like in the arrangements previously described.

It is, of course, obvious that this system may be likewise employed in three phase alternating current systems, of the character shown in Fig. 2, and the changes necessary in Fig. 2 to convert the indirect opening of the motor circuit in case of danger into a direct opening of it are similar to those alterations made in Fig. 1 and shown in Fig. 3.

What I claim is:

1. In a time limit circuit breaker the combination with an electric motor, and main conductors supplying the current thereto; of a cut out controller and auxiliary circuits connecting it with said main conductors, said controller having means responsive to an amount of motor current exceeding a predetermined limit for interrupting the connection between said mains and the motor, said controller also having means for automatically locking said interrupting means during a predetermined time to permit the starting of the motor without interrupting the main circuit.

2. In a time limit circuit breaker, the combination with an electric motor, and main conductors supplying the current thereto; of a cut out controller and auxiliary circuits connecting it with said main conductors, said controller having solenoids located in said main conductors and responsive only to amounts of motor current in excess of a predetermined limit, and cores located therein, causing the interruption of the motor circuit when their solenoids respond, means tending to lock said cores in inoperative position, means tending normally to discharge said locking means from their cores, a starting solenoid connected with said auxiliary circuits for removing said disengaging means from normal position, to render said locking means operative when it is desired to start the motor, means for closing the circuit through said solenoid, and means for deenergizing said starting solenoid to permit return of said disengaging means to normal position, a dash pot for controlling the return of said means to its normal position within a predetermined time, the solenoid cores of said controller causing the interrupting of the motor current after said predetermined time if an excess amount of current continues passing through said solenoids.

3. In a time limit circuit breaker, the combination with an electric motor, main conductors supplying the current thereto and a motor switch in said main conductors for controlling the current supply to the motor; of a cut out controller and auxiliary cir-

- cuit connecting it with said main conductor, said controller having solenoids located in said main conductors and responsive only to amounts of motor current in excess of a predetermined limit, and cores located therein, causing the interruption of the motor circuit when their solenoids respond, means tending to lock said cores in inoperative position, means normally tending to disengage 5 said locking means from their cores, a starting solenoid connected with said auxiliary circuits for removing said disengaging means from normal position to render said locking means operative when it is desired 10 to start the motor, means for closing the circuit through said solenoid, and a solenoid connected with said auxiliary circuits for closing said motor switch, a switch connected with said disengaging means for closing 15 said motor switch-solenoid circuit when said means are removed from normal position, an auxiliary switch for opening said starting-solenoid circuit and for closing a shunt to the switch operated by said disengaging means when the motor switch is 20 closed, a dash pot for controlling the return of said disengaging means to normal position within a predetermined time, the solenoid cores of said cut out controller causing 25 the interrupting of the motor current after said predetermined time if an excess amount 30 of current continues passing through their solenoids.
4. In a time limit circuit breaker, the combination with an electric motor, main conductors supplying the current thereto and a solenoid operated motor switch in said main conductors for controlling the current supply to the motor; of a cut out controller and auxiliary circuits connecting it with said main conductors, said controller having solenoids located in said main conductors and responsive only to amounts of motor current in excess of a predetermined limit, and cores located therein, means tending to lock 40 said cores in inoperative position, a weight for normally holding said locking means in inoperative position, a starting solenoid connected with said auxiliary circuits for lifting 45 said weight to render said locking means operative when it is desired to start the motor, means for closing the circuit through said solenoid, and a solenoid connected with said auxiliary circuits for closing said motor 50 switch, a switch connected with said weight for closing said motor switch solenoid circuit when in lifted position, an auxiliary switch for deenergizing the weight-solenoid 55 and for closing a shunt to said weight switch 60 when the motor switch is closed, a dash pot for controlling the dropping of said weight to its normal position within a predetermined time, the solenoid cores of said cut out controller interrupting the auxiliary circuit through said motor switch solenoid 65 after such predetermined time if an excess amount of current continues passing through their solenoids.
5. In a time limit circuit breaker, a cut out controller having two main solenoids 70 each connected in series with the main circuit to be broken, and a core for each solenoid, a latch for each core normally tending to lock its core in deenergized position, a bar disposed substantially vertically between the two solenoids having a weight attached to it resting upon both of said latches to normally unlock said cores, a starting solenoid having its core connected with said bar, and a dash pot also connected with said bar permitting free upward movement of said bar and said weight when said core is drawn in by its solenoid, but causing said weight to drop within a predetermined time when said starting solenoid is deenergized, a switch adjacent to each core of said main solenoids normally tending to remain closed, said switches having suitable connection with the main motor circuit, whereby the latter is 80 opened when said switches are opened, the cores of said main solenoids adapted to open said switches when their solenoids are energized by a current exceeding the predetermined limit, and said weight is resting in normal position, said latches preventing said 85 cores from rising and opening said switches so long as the weight remains in raised position.
6. In a time limit circuit breaker, the combination with an electric motor, and main 90 conductors supplying the current thereto; of a cut out controller, auxiliary circuits connecting it with said main conductors, said controller having means responsive to an amount of motor current exceeding a predetermined limit for interrupting the connection between said means and the motor, said controller also having automatically operating means for rendering said interrupting means inoperative during a predetermined time to permit the starting of the motor without interrupting the main circuit. 95
7. In combination, an electro-responsive switch, an electro-responsive relay associated therewith and deenergized upon operation thereof and an overload tripping device for said switch, said relay when energized rendering said device ineffective and having means for retarding its operation when deenergized to maintain said switch independent of said device for a definite period after operation of the former. 105
8. In a motor controller, in combination, electro-responsive starting means, overload tripping means and an electro-responsive relay responsive to energize said starting means and to render said overload means ineffective, said relay being deenergized upon response of said starting means and having means for retarding its return move- 115
- 120
- 125
- 130

6
ment to prolong the period of ineffectiveness of said tripping means.

9. In combination, a protective device for electric circuits, electromagnetic means controlling the continuity of the circuit to be protected and means interlocked with said former electromagnetic means to render said protective device ineffective for a temporary period after closure of the circuit to be protected.

10. The combination with an automatic protective device comprising a switch controlling the continuity of the circuit to be protected and an electromagnetic tripping device therefor, and electro-responsive means responsive prior to closure of said switch to render said tripping means ineffective and deenergized upon closure of said switch to render said tripping means effective after a temporary period.

11. The combination with an automatic protective device, including a switch controlling the continuity of the circuit to be protected and an electromagnetic tripping device therefor, an electro-responsive device responsive to render said tripping device ineffective and having means for retarding its movement when deenergized, said electro-responsive device and said switch being interlocked to necessitate energization of the former prior to closure of the latter and to deenergize the former upon closure of the latter.

12. The combination with an automatic protective device including an electro-responsive switch controlling the continuity of the circuit to be protected and an overload tripping device therefor of an electro-responsive device responsive to mechanically lock said overload device against operation and having means for retarding its operation to release said overload device, and electrical interlocks between said electro-responsive device and said electro-responsive switch necessitating energization of the former prior to energization of the latter and effecting deenergization of the former upon response of the latter.

13. In combination, an automatic protective device for electric circuits and means operable to mechanically lock said device against operation, said means tending to

automatically operate to release said device and means for retarding the automatic movement of said former means to maintain 55 said device locked for a definite period of time.

14. In combination, a protective device for electric circuits and means for mechanically locking said device prior to closure of 60 the circuit to be protected and automatically releasing said device after the lapse of a predetermined period of time.

15. In combination, an automatic protective device for electric circuits, electro-responsive means for mechanically locking said device against operation prior to closure of the circuit to be protected, means for automatically deenergizing said electro-responsive means, and means retarding the operation of said locking means after deenergization thereof to maintain said protective device locked for a predetermined time after completion of the circuit to be protected. 75

16. In combination, an electric circuit, an automatic protective device therefor, and means automatically locking said protective device against operation prior to closure of said circuit and automatically releasing said 80 device upon the lapse of a predetermined period of time.

17. In combination, an automatic protective device for electric circuits, electromagnetic means controlling the continuity of 85 the circuit to be protected, and electromagnetic means interlocked with said former means to render said protective device ineffective prior to closure of the circuit to be controlled and to subsequently render said 90 protective device effective.

18. In combination, an automatic protective device for electric circuits, means controlling the continuity of the circuit to be protected and means interlocked with said 95 former means to render said protective device ineffective upon closure of the circuit to be controlled and to automatically render said protective device effective after the lapse of a definite period of time.
